UNITED STATES PATENT OFFICE

KINNEY TJSSEM, OF PAULLINA, IOWA

FLY CHASER.

Application filed April 16, 1928. Serial No. 270,307.

My invention relates to a device for removing flies from the edge of a screen door and has for its general object to provide such a device attachable to a screen door so as to be operated by swinging movement of the door.

More particularly, it is my object to provide such a device including a brush and means for rotating said brush, when the door is opened, in such a manner as to sweep flies from the edge of the door.

A further object of my invention is to provide actuating mechanism, designed to multiply the relative movement between two points situated rather closely adjacent either side of the door hinge axis.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is an elevation of a portion of a screen door and its adjacent casing, with my invention attached thereto.

Fig. 2 is a horizontal, sectional view through the casing just above the door.

Fig. 3 is a detail, sectional view taken on the line 3—3 of Fig. 2.

Fig. 4 is a detail, sectional view taken on the line 4—4 of Fig. 3.

Fig. 5 is a view illustrating a somewhat modified and simplified form of the actuating mechanism.

I have used the reference character 10 to indicate generally the door casing of a housing. The screen door comprises the upper frame member 11 and the side members 12 and 13, the latter being hinged to the casing 10, as at 14.

My invention comprises a frame structure including a long bar 15, adapted to be attached as at 16 to the vertical frame members 12 and 13 and a short member 17, hinged to the lower member 15, as at 18 and adapted to be attached, as at 19, to the door casing 10.

Mounted in the frame bar 15, near one end, thereof, is a stud 20, on which is journaled

a sleeve 21. At one end, the sleeve 21 supports a brush frame 22 and at its other end it forms a pinion 23. The brush frame 22 is provided with arms 24, adapted to receive pieces of rag 25. When the brush is rapidly rotated, the rags 25 will swing radially by a centrifugal force and will act to remove the flies from the edge of the door.

Coacting with the pinion 23 is a longitudinally slideable rack bar 26, which is held in engagement with the pinion by means of a finger 27, formed on the frame bar 15. One end of the rack bar projects toward the hinge of the screen door and is there pivoted to some form of mechanism for giving to it longitudinal motion when the door is opened. The preferred form of this mechanism is shown in Figs. 1 and 2 and comprises generally a bell crank lever, having the arms 28 and 29, the former being substantially parallel to the plane of the door when closed and connected to the frame bar 15 by means of a link 30 and bracket 31 and the latter being substantially perpendicular to the door when closed and being connected to the rack bar 26 by means of a link 33. The bell crank lever is fulcrumed, as at 32, upon a bracket 34, which may be formed integrally with the frame member 17. Instead of using the bell crank lever and link 30, the link 33 might be fastened directly to the bracket 34, as shown in Fig. 5. In the latter case, as the door is swung open, as indicated by the arrow 36, that point of the door opposed between the rack bar 26 and the link 33 will move toward the bracket 34, thereby causing the rack bar 26 to move relative to the door. This advance will cause the pinion 23 to be rotated revolving the brush. However, the amount of motion thus obtained is hardly sufficient, and furthermore, the motion is slow with the beginning of the swing and accelerates as the door swings outwardly. It is my purpose in employing the mechanism shown in Figs. 1 and 2 to obtain a maximum amount of motion at the beginning of a swing.

This is due to the fact that the arm 27 imparts greater longitudinal movement to the rack, swinging faster while swinging substantially perpendicular to the casing 10 than

after it has passed that position. It may be further noted that as the door opens, it not only moves toward the end of the arm 29 but it forces the arm 21 to swing in the direction indicated by the arrow 37, thus multiplying the relative movement of the door and the rack bar.

It will be noted, by inspecting the dotted line position shown, that when the door is fully opened, the end of the arm will have swung from a position beyond the center of the casing away from the door to a position where it has passed the hinge of the door and is adjacent the door frame.

15 Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

25 1. In combination with a door and its casing to which it is hinged, a brush mounted on the door for movement to remove flies from the door, a member secured to the casing and projecting therefrom so that movement of the door will bring it nearer to said member,

30 means connected to the brush to impart movement thereto when moved relative to the door, a bell crank lever fulcrumed on the projecting member, one arm thereof projecting toward the casing when the door is closed and being connected to said means and a link connecting the other arm thereof with the door, said other arm projecting toward the door, whereby movement of the door may swing the bell crank lever so as to move said means relative to the casing to add to the movement of said means relative to the door caused by swinging of the door relative to said projecting member.

35

40

2. In combination with a door and its casing to which it is hinged, a brush mounted on the door for rotating movement to remove flies from the door, a member secured to the casing and projecting therefrom so that movement of the door will bring it nearer to said member, a pinion on the brush, a longitudinally slideable rack meshing with said pinion, a bell crank lever fulcrumed on the projecting member, one arm thereof projecting toward the casing when the door is closed, a link connecting said last mentioned arm to the rack and a second link connecting the other arm thereof with the door, the parts being so arranged that movement of the door may swing the bell crank lever so as to move the rack relative to the casing to add to the movement of said rack relative to the door caused by swinging of the door relative to said projecting member.

3. In combination with a door and the casing to which it is hinged, a metal bar secured

to the door in a horizontal position, a bracket hinged to one end of said bar and adapted to be secured to the casing, said bracket having a projecting member, a brush rotatably mounted on the metal bar in a position to remove flies from the door upon rotating a pinion on the brush, a longitudinally sliding rack meshing with said pinion, a lug formed on the bar and extending over the rack to retain it in engagement with the pinion, said rack being connected to the projecting member in such a way that swinging movement of the door will cause the rack to move longitudinally of the bar and to transmit rotating movement to the brush. 70 75 80

Signed this 3rd day of April, 1928, in the
county of O'Brien and State of Iowa.
